DESIGN FOR A STOCKING OR SIMILAR ARTICLE

Erwin Camp, New York, N. Y.

Application December 19, 1940, Serial No. 97,461

Term of patent 3½ years

To all whom it may concern:

Be it known that Erwin Camp, a citizen of no country, but having declared his intention of becoming a citizen of the United States and resident of New York, in the county and State of New York, has invented a new, original, and ornamental Design for a Stocking or Similar Article, of which the following is a specification, reference being had to the accompanying drawing, forming part thereof, in which the figure is an elevational view of a stocking embodying my new design.

I claim:

The ornamental design for a stocking or similar article, substantially as shown.

ERWIN CAMP.
